Primary Examiner — Paula Allen Greene(74) *Attorney, Agent, or Firm* — Cantor Colburn LLP(57) **CLAIM**

The ornamental design for an earphone, as shown and described.

DESCRIPTION

FIG. 1 is a front perspective view of an earphone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a right side perspective view thereof; and,

FIG. 9 is another front perspective view thereof in an environment of use.

The broken lines illustrating portions of the earphone and the environment of use form no part of the claimed design.

1 Claim, 9 Drawing Sheets---
